UNITED STATES PATENT OFFICE

ALBERT F. BEMIS, OF NEWTON, MASSACHUSETTS, ASSIGNOR TO BEMIS INDUSTRIES INCORPORATED, OF BOSTON, MASSACHUSETTS, A CORPORATION OF DELAWARE

BUILDING CONSTRUCTION

Application filed December 14, 1929. Serial No. 414,056.

This invention relates to an improved method of building construction and resulting products, and involves the employment of parts that are manufactured in quantities and which do not require cutting in situ, and greatly facilitates the construction of dwelling houses or the like, while not precluding versatility in design or necessitating a standardized or stereotyped appearance. Some aspects of the present invention are further developments of the subject matter disclosed and claimed in my prior application, Serial No. 280,226, filed May 24, 1929.

Mass production of most fabricated articles of daily use has become almost universal and their cost consequently has been reduced, often with an increase in accuracy of construction, due to the efficiencies of large scale production. On the other hand, the desirability of individuality and distinctiveness in the appearance of buildings and particularly of frame dwellings has caused the general retention of substantially the same methods as have been employed for generations, thus requiring much laborious cutting and fitting of individual parts and the like to secure the desired variation in design. Thus the cost of home construction has tended to rise in relation to that of most fabricated articles, and consequently the expenditure for shelter forms a larger proportion of the average individual's living expenses than heretofore.

The primary object of the present invention is to lessen or eliminate this discrepancy between the cost of buildings, such as the type that has ordinarily been characterized by wooden frames, and that of other fabricated articles and to permit the recognized advantages of large scale production to be adapted to this field of activity without sacrificing versatility in design or involving a standardized appearance in the finished buildings. For example, my invention may be advantageously employed to provide substantially any desired layout or arrangement of rooms, placing of doors, windows, etc., and permits the employment of practically any style of interior or exterior finish, so that it may be impossible without actual detail measurements to determine whether or not houses

of widely varying types have been constructed in accordance with my method or the inefficient methods heretofore employed.

The present invention reduces the cost of materials and labor in erecting building structures by permitting mass production of frame members such as columns, posts, girts, joists, and studs which are capable of combination without further cutting and fitting to form substantially any building design without requiring alteration in the process of erection, and which facilitates the assembly of the parts of the building frame and permits the use of standardized forms or slabs in laying the foundations without sacrificing latitude in the choice of size and shape, the ready employment of doors and windows in a convenient range of sizes, as well as the general employment of preformed structural or finish elements, such as slabs, panels, tiles, lathing sections and the like, to the end of minimizing the cost of materials and labor of erection while facilitating accuracy of construction.

According to this invention, the primary frame members such as girts, sills, posts, columns, and the like, may be manufactured with a determined interdimensional relationship, being provided with uniform means to facilitate their connection to each other upon assembly, which may, for example, comprise connecting brackets and may be formed with reference to the dimensional relationship. Furthermore, the primary frame members, such as sills and girts, may then be provided with repetitive means arranged with reference to the general dimensional relationship of the parts to facilitate and assure the proper arrangement of parts such as door and window frames and of secondary frame elements such as studs or joists. The latter may also have a dimensional relationship to the primary or main structural members such as the girts, which corresponds to and is dependent upon general interdimensional relationship of the primary or main frame members, so that these parts may also be preformed and fitted and connected with the primary elements without necessity for cutting in situ.

In the accompanying drawings:

Fig. 1 is a plan view of a building frame showing the arrangement of elongate members such as girts disposed between posts to provide an irregular floor plan;

Fig. 2 is an elevational view showing the arrangement of a typical girt and posts at the ends of the same;

Fig. 3 is a similar view of the arrangement of a post between the ends of two girts;

Figs. 4 and 5 are views similar to Fig. 3, but showing the adaptation of the principles of this invention to somewhat different structural arrangements;

Fig. 6 is a diagrammatic view of a typical arrangement of girts and joists or the like;

Fig. 7 is a plan view of a building frame or showing another arrangement of girts and posts;

Fig. 8 is a perspective view of a part of a structural frame and wall which may be arranged in accordance with the arrangement shown in Fig. 7;

Fig. 9 is a plan view of a portion of the wall structure as shown in Fig. 7 showing the arrangement of the parts in greater detail;

Fig. 10 is a view partly in elevation and partly in section of the wall disclosed in Fig. 8;

Fig. 11 is an elevational detail of the juncture of a post and two aligned girts;

Fig. 12 is a perspective view of a portion of a girt and stud;

Fig. 13 is a similar view of a bracket for connecting a girt to a joist;

Fig. 14 is a broken perspective detail of a wall slab or panel; and

Fig. 15 is a perspective view of a portion of a stud.

The principles of my invention may be applied to building constructions having rooms of various types, for example, with the elongate primary members such as girts disposed upon brackets extending from the vertical posts or columns and with the latter arranged at the ends of the girts, with the girts extending into recesses in the posts or with the posts extending between the girts for successive stories. In fact, substantially any method of joining the frame members to each other may be arranged to comply with the interdimensional relationships set forth herein.

Fig. 1 is a diagrammatic representation of the frame of a house having an irregular floor plan and provided with rooms G, H, I, J, L and O, the latter providing a bay extending from one side of the house. The posts are designated in general by the symbol

P and are arranged at the corners or intersections of wall portions of the frame. As shown, the frame adjoining the room O may be provided with five girts numbered 1, 2, 3, 4 and 5, respectively, the girts 1, 4 and 5 forming a portion of the framework of the

outer walls of the house, the girt 2 defining the partition between the rooms O and L, the girt 3 forming a part of the wall structure between rooms O and I. Elongate primary frame members 6 and 7 are disposed at the outer ends of rooms J and L, which are separated from each other by the partition girt 9 and are separated from the room H by girts 11 and 12. The room J is also provided with another wall portion that forms a part of the outer wall of the building and which includes member 13, while a girt 15 forms a part of the partition separating the room L from one end of room I.

Rooms H and I are separated from each other by a frame including the member 17, and the girts 18 and 19 are disposed at the remote ends of these rooms, while girts 20 and 21 separate them from the room G, the other three sides of the latter being defined by members 23, 24 and 25.

Ordinarily the employment of an irregular floor plan of the character illustrated would entail the cutting or special fitting of some of the intermediate girts 11, 12, 15, 3, 20, 21, or the like. I have discovered, however, that the parts may have an interdimensional relationship with one another so that the frame members may be disposed to provide substantially any room layout with various numbers of intermediate walls between parallel outer walls and with various bays or the like, while permitting the use of the preformed structural members.

To permit this desirable result, the elongate frame members or girts may conveniently be made to differ in length from each other by a multiple of a predetermined modular dimension M, this dimension being chosen to permit the graduation of room dimensions by relatively small amounts, such for example as 4, 6, 8 or 10 inches, and also being chosen to be of the order of the desired thickness of the structural wall portions, and particularly of the intermediate structural walls. Thus, for example, let us assume that a module of 8 inches is chosen as complying with the above requirements; then each of the elongate primary frame members, such as girts, is provided with a length which may differ from that of other similar members by an integral multiple of 8 inches; in other words, the preformed girts may be manufactured in lengths which are equal to different multiples of the module M plus a determined constant K, the latter being a dimension less than 8 inches.

Figs. 1, 2 and 3 illustrate the application of these principles to building frames having uniform connecting arrangements between the posts and girts; for example, structural members such as posts may be provided with brackets B which hold the frame members such as girts in spaced relationship to the adjoining parts of the structural members.

For convenience of explanation I herein-after refer to the uniform distances at which the ends of the girts are spaced from the posts as being represented by the symbol C, and the cross-sectional dimension of the post which is disposed at or between the ends of the girts as represented by the symbol W.

I have found that the proper proportioning of the dimensions M, K, C and W permits the use of the elongate frame members without necessity for cutting to special lengths. The general relationship which permits this desirable result may be conveniently stated by the formula $2C + K + W =$ an integral multiple of M, (it being understood that in certain applications of the invention C and/or K may equal zero, and the multiple may be one). Thus, for example, the lengths of the various outer and intermediate girts shown in Fig. 1 may each be equal to K plus an integral multiple of M, K being a dimension chosen to conform with the above formula; thus, for example, in the illustrated embodiment of the invention K may be 3 inches, the cross-sectional dimension of the adjoining part of the post having been dimensioned as $3\frac{1}{2}$ inches, and the clearance dimension C having been made $\frac{3}{4}$ of an inch. Thus the dimensions being substituted in the formula $2C + K + W =$ an integral multiple of M, the following equation will result: $1\frac{1}{2}'' + 3'' + 3\frac{1}{2}'' = 8''$ (8" being one module).

The various modular dimensions of the girts in the floor plan illustrated in Fig. 1 are indicated adjoining the corresponding members, and it is evident that despite the irregular layout of the rooms and partitions that girts of standardized length may be employed throughout and flexibility of design and layout secured.

As illustrated, for example in Fig. 2, the employment of this interdimensional relationship of parts will ordinarily result in the centre planes of parallel walls being spaced at multiples of the modular dimension, although the exterior walls may, if desired, be provided with a structural thickness greater than that of the intermediate walls so that their centre planes will not be modularly spaced.

Fig. 4 illustrates a somewhat different manner of connecting the girts and post. In this case girts 30 and 31 have extensions or tongues 32 and 33 which are disposed in recesses 34 in the post P¹. In this figure the girts are illustrated as being in direct engagement with the intervening part of the post so that there is no clearance and so that the dimension C equals zero, the dimension W being the distance between the inner ends of the recesses, M being chosen as before. It is evident that the dimensions of the parts, when arranged in the manner illustrated in Fig. 4, may still readily be chosen to comply

with the formula $2C + K + W =$ an integral multiple of M, and it will be found that this arrangement could be employed with equal facility in permitting practically any desired wall layout. The constant K may be a dimension which is smaller than the depth of one of the tongues 32 and 33 or greater than the same.

Fig. 5 illustrates another possible arrangement for connecting the girts and posts wherein the connecting elements 36 extend outwardly beyond the post and hold the girts in spaced relation thereto, while having their opposite ends received in recesses 37 within the post. In this embodiment of the invention the distance between the inner portions of the recesses may determine the cross-sectional dimension W, and the clearance dimension C may be chosen as the space between the end of the girt and the inner wall of the adjoining recess. When this type of connection is employed and the parts are proportioned to comply with the formula $2C + K + W =$ an integral multiple of M, the same advantageous relationship of the parts may be maintained.

Not only are the principles of this invention applicable to the proportioning of the dimensions of the main or primary members of the building frame such as sills, girts, columns and posts, but they are also advantageously employed in conjunction with the dimensions of the secondary frame members such as girders or joists which span the spaces between the parallel girts.

Fig. 6 illustrates a typical arrangement which may be employed with the girts providing ledges to support the ends of intervening frame members such as joists 40. If the frame is proportioned and erected to conform with the interdimensional principles set forth above, the same general relationship may be readily attained in conjunction with the joists or the like, these members also differing in length from each other by a multiple of the module M. For example, the equation $2c + w + k =$ an integral multiple of M is applicable to the dimensioning of the secondary members such as joists in conjunction with the adjoining dimensional portions of the girts or the like. Thus w represents the cross-sectional dimension of the girt, c the clearance space between this portion of the same and the end of the joist, and k the constant which is added to an integral multiple of M in determining the lengths of each of the joists; for example, the dimension w may equal $2\frac{1}{2}''$, the clearance c may equal $\frac{1}{2}''$, and k may then equal $4\frac{1}{2}''$ so that

$$2c + w + k = 1M(8'')$$

Furthermore, it is advantageous to provide the frame members such as girts with repetitive means for connecting the secondary frame elements such as studs and joists there-

to. Preferably such connecting means may be symmetrically arranged in relation to the ends of the girts, sills, or the like, and may be spaced at modular distances from each other, that is, at multiples or equal divisions of the same. For example, the connecting means may be spaced $1/2k$ for the ends of the girts and spaced at distances of one module from each other; the resulting arrangement of the secondary frame members such as joists 40 is illustrated in Fig. 1, these members being spaced from each other at uniform distances which are multiples of the module, i. e., two M, and the end joists being spaced $1/2k$ or $1M + 1/2k$ from the ends of the corresponding girts, and being so disposed as to permit the arrangement of a post at any determined point. Thus the placing of the secondary frame members is facilitated, and it is not necessary to provide a special arrangement of the same when a post is disposed between the ends of aligned girts, as exemplified, for example, by the post between girts 20 and 23 or between girts 12 and 15. Similarly the arrangement of the secondary frame members which are disposed in a plane at right angles to that of the load bearing members is also facilitated.

Figs. 7, 8, 9, 10 and 11 illustrate a somewhat different arrangement of frame members and the application of this invention to one definite type of building construction such as is disclosed and claimed in my copending application, Ser. No. 414,350 filed on even date herewith; Fig. 7 shows a building having an irregular room layout, the rooms S and T occupying one side of the building, and the room R having a length corresponding to that of both of the rooms S and T. The girts 50 and 51 separate rooms S and T from room R, and the girt 53 parallel to members 50 and 51 defines the opposite wall of room R while girts 55 and 56 extend along its ends. The members 58 and 59 are aligned with girts 55 and 56 respectively and define the outer ends of rooms S and T while their sides, which are remote from room R are provided with girts 60 and 61 and the girt 63 is disposed between these rooms.

The posts are designated in general by the reference character P' and the various dimensions of the girts are designated adjoining the same. Thus for example the girts 50 and 60 may have lengths of 13 modules plus a constant K (which may have any value from 0 to a module M); the girts 51 and 61 may have a length of 17 modules plus K, while the girt 53 has a length of 32 modules plus K.

It is to be understood that the principles of this invention may be employed when $2C + K + W = 1M$, $2M$ or any integral multiple of M. For example in the embodiment of the invention illustrated in Fig. 7

$$2C \pm W + K = 2M$$

Fig. 8 shows structural details of a building, such as is disclosed and claimed in my copending application Ser. No. 414,350, filed on even date herewith to which the principles of this invention may be applied. Posts P' of this frame, in the illustrative example here given are equilateral cross-section and are provided with outstanding flanges 65 disposed at the corners of an intermediate square portion 66 and being located at angles of 135° to the adjoining walls of the square section 66. Brackets 67 may have side portions secured by fastening elements 68 to the flanges 65 and may include intermediate cross members 73, each of which is connected by a fastening element 70 to a lip 69 at the end of a girt; thus brackets 67 and associated fastening means serve to secure the girts to the posts.

Preferably the girts may be of box-like cross-section as disclosed in Fig. 12, having upper and lower plates 72 which may be cut away at the ends of the girts to permit bracket plates 69a to be placed in alignment therewith; these plates preferably extend outwardly beyond the end of the girt and have lips 69 formed integrally therewith. The edges of the plates 72 are preferably secured as by welding to the channels 74 which form the vertical walls of these frame members. The legs of the channels and the juxtaposed edges of the plates cooperate in providing outstanding horizontal flanges 75 upon the girts. The plates 73 may be provided with a plurality of intermediate openings 80 which are spaced in accordance with the modular dimensioning of the parts while the flanges 75 may be provided with openings 78 and/or have brackets 85 secured thereto which are also spaced at modular distances or multiples of the same from each other. Thus for example brackets 85 (Figs. 8 and 13) may be provided with a depending portion adapted to receive the ends of joists 86 and with outstanding flanges 87 having openings 88 to register with the openings in the flanges 75 so that the brackets are readily secured to the upper flanges of the girts. Since the openings 88 are symmetrically disposed in relation to the brackets 85, joists 86 will have their center lines disposed substantially one-half way between the modularly spaced openings 78.

The vertical frame elements or studs 95 (Fig. 15) each comprise a pair of similar spaced channel portion 96 with flanges 97 extending outwardly from the legs of the channel portions in a direction at right angles to the plane of the wall in which the studs are incorporated. The upper and lower ends of the channels 96 are joined to plates 98 which may be provided with suitable openings 108 to register with openings 78 at opposite sides of the girt and to receive fastening elements to permit the connection of the studs

70

130

to the horizontal frame members. The plates 98 are also preferably provided with openings 109 to register with the openings 80 in the girts. Preferably the channels 96 receive the edges of wall plates 100 which may also engage the recesses provided by adjoining flanges 65 upon posts P'. The wall slabs or plates 100 may conveniently comprise an intermediate sheet or board of insulating material 101 and rectangular marginal frames 103 extending outwardly beyond the edge of the board 101 to provide marginal grooves 104. Preferably the bight portions of channels 96 are provided with openings 112 which register with the vertical grooves 104 upon the adjoining wall plates. The legs of channels 96 and the flanges 97 provide angle portions at each side of the stud adjoining the face of the structural wall, which receive the edges of nailing strips 114. If desired, suitable openings 115 may be provided in the flanges 97 to receive fastening elements such as nails 117 that hold the strips 114 in place.

Each of the girts obviously provides a trough-like portion into which cementitious material may be poured through the openings 80 in the upper plate 72, this cementitious material passing downwardly through openings 80 in the lower plate of each girt into the groove at the upper edge of the wall plate 100 or into a vertical recess provided by the channels 96 and boards 114 of a stud 95, as the case may be. From this recess the cementitious material may flow through openings 112 into the corresponding groove 104 so that each of the studs is reinforced by poured cementitious material which has a keying engagement with marginal recesses of the adjoining wall plates, while the horizontal margins of the plates also may similarly be keyed to the horizontal frame members or girts.

To permit the application of the principles of this invention to a building construction of the type just described, it may be assumed that M equals four inches, that the cross-sectional dimension W of the post is four and one-half inches, that C as determined by the construction of brackets 67 and bracket plates 69 and by the necessary mechanical considerations equals one-quarter inch and accordingly that K equals three inches in order to meet the requirements of the formula $2C + K + W = a$ multiple of M, i. e. $\frac{1}{2}'' + 3'' + 4\frac{1}{2}'' = 8''$ or $2M$. This modular relationship of the parts is particularly illustrated in Fig. 11, the openings 78 and 80, adjoining the ends of the girts are spaced $\frac{1}{2}K$ from the same, and are located at one module from each other. Inasmuch as K cannot exceed one module the distances ($\frac{1}{2}K$) between the end openings 78 and 80 and the ends of the members are not greater than $\frac{1}{2}M$. It is thus evident that the joists 86 may be disposed at multiples of the module from each other, as shown in Fig. 10, as for

example being located at four modules or sixteen inches center to center distance from each other, while the wall plates 100 may be provided in widths which differ from each other by the module and may be located with their edges in engagement with the studs as shown. The openings 80 will then register with the openings 109 and the recesses in the studs to permit the pouring of cementitious material which may also fill the adjoining trough-like portion of the girt and thus may provide a concrete frame member with a metal shell having cementitious extensions defined by units disposed within the wall.

Obviously the joists 86 may be provided in a range of standardized lengths which differ from each other by multiples of the modular dimension in the same manner as set forth with reference to Fig. 6.

The dimensional interrelationship of the parts of the building may be applied to both their vertical and their horizontal dimensions, if desired. Thus the posts and studs may be provided in lengths which differ from each other by the modular dimension or multiples of the same, if desired, and the openings in these members for connection to the brackets 67 and the nailing strips 114 may be disposed at a modular distance from each other, if desired.

With the modular interrelationship applied to the vertical structural members (posts) and wall members (studs) as well as the horizontal structural members (girts) and horizontal wall or floor members (joists), as described in the preceding paragraph, it will be evident that the planes of each of the three sets of mutually perpendicular, horizontal and vertical walls are spaced at integral multiples of the module as illustrated in Fig. 2 and that the space-matrices between these planes corresponding to each room are resolvable into cubes identical in dimensions of one module on a side.

While the dimensions selected by way of example in regard to Figs. 7, 8, 9 and 10 illustrate how the principle of the invention may be applied when W is greater than the module and Figs. 1, 2 and 3 illustrate the employment of the invention when W is less than M, it is to be understood that, if desired, W may equal M. Thus in the example of invention illustrated in Fig. 7 post P' might be made to have a cross-sectional dimension of four inches so that W then will equal M and so that the principles of this invention may still readily be employed.

I claim:

1. The new and improved method of building which involves quantity manufacture of preformed building units and avoids cutting in situ, which comprises forming frame members in a plurality of lengths which differ from each other by multiples of a predetermined module M, whereby

frame members are developed of lengths equal to integral multiples of the module M plus a constant K ; forming structural members with a predetermined cross sectional dimension W , and then connecting said frame and structural members into a building frame, with the ends of said frame members uniformly disposed relative to the aforesaid cross-sectional parts of the structural members so that $2C + K + W$ equals an integral multiple of M , the quantity C equaling the spacing of a frame member from the cross sectional part of the structural member.

2. The method of building as specified in claim 1 involving further providing certain of said members with means spaced from one another at multiples of module M to connect intermediate frame members such as studs or joists, forming such intermediate frame members in lengths differing by a multiple of module M , positioning the members having the modularly spaced connecting means in parallel relation and coupling said intermediate frame members thereto by said connecting means.

3. The method of building as specified in claim 1 involving further providing certain of said members with openings spaced from one another at multiples of module M to connect intermediate frame members such as studs or joists, forming such intermediate frame members in lengths differing by a multiple of module M , positioning the members having the modularly spaced openings in parallel relation, and coupling said intermediate frame members thereto by said openings.

4. The new and improved method of building which involves quantity manufacture of preformed building units to avoid cutting or fashioning in situ, which comprises forming structural members with cross-sectional dimensions W and primary frame members with cross-sectional dimensions w and lengths which differ from each other by multiples of a module M , and thus may each have a length equal to an integral multiple of M plus a constant K , positioning the primary frame and structural members with the ends of the former juxtaposed to parts of the latter that have the cross-sectional dimension W , so that $2C + K + W$ equals an integral multiple of module M , when C equals the spacing between the end of a primary frame member and the juxtaposed part of the structural member, forming secondary frame members having lengths which differ by multiples of the module M and the lengths of which may equal integral multiples of M plus a constant k , and providing uniformly spaced connecting means on the primary frame members, coupling the ends of the secondary members to the primary

frame members in a uniform manner by said means, so that $2c + k + w$ equals an integral multiple of module M , when c equals the spacing of the end of a secondary frame member from the juxtaposed part of a primary frame member having the cross-sectional dimension w .

5. A building having walls made up of parallel frame portions including parallel structural members, an elongate primary frame member spanning the distance between structural members in said parallel frame portions, an intermediate structural member parallel to the structural members in said frame portions, and primary frame members at right angles to and spanning the distance between the intermediate structural member and structural members in said frame portions, uniform connecting means joining the frame members to the structural members, the frame members having lengths which differ from each other by equal multiples of a module M , so that their respective lengths may be equal to integral multiples of M plus a constant K , the intermediate structural member having a portion between the adjacent ends of frame members, said portion having a cross-sectional dimension W in the direction of length of the frame members, the parts being so proportioned that when C equals the spacing of each of the frame members from said portion of the structural member between the ends of said frame members, $2C + W + K$ equals an integral multiple of M .

6. A building having walls made up of parallel frame portions including parallel structural members, an elongate primary frame member spanning the distance between structural members in said parallel frame portions, an intermediate structural member parallel to the structural members in said frame portions, and primary frame members at right angles to and spanning the distance between the intermediate structural member and structural members in said frame portions, uniform connecting means joining the frame members to the structural members, the frame members having lengths which differ from each other by equal multiples of a module M , so that their respective lengths may be equal to integral multiples of M plus a constant K , the intermediate structural member having a portion between the adjacent ends of primary frame members, said portion having a cross-sectional dimension W in the direction of length of the frame members, the members being so proportioned that when C equals the spacing of each of the frame members from the cross-sectional dimension of the structural member between the ends of said frame members, $2C + W + K$ equals an integral multiple of M , connecting means upon said primary frame members spaced uniformly at multiples of M ,

and secondary frame members extending between the primary frame members, and uniformly coupled thereto by said means.

7. A building having walls made up of parallel frame portions including parallel structural members, an elongate primary frame member spanning the distance between structural members in said parallel frame portions, an intermediate structural member parallel to the structural members in said frame portions, and primary frame members at right angles to and spanning the distance between the intermediate structural member and structural members in said frame portions, uniform connecting means joining the frame members to the structural members, the frame members having lengths which differ from each other by equal multiples of a module M , so that their respective lengths may be equal to integral multiples of M plus a constant K , the intermediate structural member having a portion between the adjacent ends of primary frame members, said portions having a cross-sectional dimension W in the direction of length of the frame members, the members being so proportioned that when C equals the spacing of each of the frame members from the cross-sectional dimension of the structural member between the ends of said frame members, $2C$ plus W plus K equals an integral multiple of M , connecting means upon said primary frame members spaced uniformly at multiples of M , and secondary frame members extending between the primary frame members, and uniformly coupled thereto by said means, certain of said frame members having cavities with openings thereto spaced at multiples of M , other frame members in registry with said openings and providing recesses, and cementitious material in the interconnected cavities and recesses of said members.

8. A building of the type having a frame assembled of manufactured parts and including frame portions defining walls parallel and at right angles to each other, comprising structural members in said frame portions, elongate primary frame members in said frame portions and spanning the distance between structural members, the primary frame members each having a plurality of uniformly spaced repetitive apertures therein symmetrically spaced from the ends of the members, uniformly spaced connecting means including certain of the apertures adjoining the ends of the frame members and joining the latter to the structural members, the frame members having lengths which differ from each other and having their apertures uniformly spaced from one another by multiples of a module M , so that their lengths may be integral multiples of M , plus a constant K , the structural members having portions at and between the ends of said frame members of a cross-sectional dimension W in the direc-

tion of the length of the frame members, with the parts so proportioned that, when C equals the spacing of each of the frame members from the cross-sectional dimension W of the structural members, $2C$ plus W plus K equals an integral multiple of M , secondary frame members spanning the space between parallel frame members, and connections including apertures on the primary frame members joining the secondary frame members to the primary frame members, said secondary frame members differing in length from each other by multiples of the module M , so that their lengths may be an integral multiple of M plus a constant k , the primary frame members having portions of a cross-sectional dimension w at and between the ends of the secondary frame members, so that when c equals the spacing of each of the secondary frame members from said portions of the primary frame members, $2c$ plus w , plus k , equals an integral multiple of M .

9. A building of the type having a frame constructed of parts that are manufactured in quantity and preformed to avoid cutting or fashioning in situ, comprising parallel frame portions defining walls and including structural members, a primary frame member extending between said structural members, an intermediate structural member parallel to structural members of said frame portions, primary frame members at right angles to and spanning the distances between the intermediate structural member and respective structural members in said parallel frame portions, uniform bracket connections joining the frame members to the structural members and holding the ends of the frame members in spaced relation to the structural members, the frame members having lengths which differ from each other by multiples of a module M that is of the order of the thickness of said frame portions, so that the respective lengths of the frame members may be equal to integral multiples of M plus a constant K , the intermediate structural member having a portion between the bracket connections, said portion having a cross-sectional dimension W in the direction of length of the frame members, the parts being so proportioned that when C equals the spacing of each of the frame members from said portion of the structural member that is between the bracket connections, $2C$ plus W plus K equals an integral multiple of M .

10. A building of the type having a frame constructed of parts that are preformed in quantity to avoid cutting and fashioning in situ, comprising frame members extending along the intersections of walls in parallel planes and structural members extending along the intersections of walls and being at right angles to the frame members, said structural members having portions disposed at and between the ends of the frame members,

- uniform connecting means securing the ends of the frame members to the structural members, the frame members having lengths which differ from each other by equal multiples of a module M , so that their respective lengths may be equal to integral multiples of M plus a constant K , the structural members having portions between the adjacent ends of frame members, said portions having a cross-sectional dimension W in the direction of length of the frame members, the parts being so proportioned that when C equals the spacing of each of the frame members from said portions of the structural members at and between the ends of said frame members, $2C$ plus W plus K equals an integral multiple of M , the structural members also having respective lengths which differ by equal multiples of a module M , the central planes of parallel vertical and of horizontal walls respectively being spaced at integral multiples of the module M so that the central planes of the walls enclosing the various rooms of the building define space matrices resolvable into cubes of M .
11. A building of the type having a frame constructed of parts that are preformed in quantity to avoid cutting and fashioning in situ, comprising frame members extending along the intersections of walls in parallel planes and structural members extending along the intersections of walls and being at right angles to the frame members, said structural members having portions disposed at and between the ends of the frame members, uniform connecting means securing the ends of the frame members to the structural members, the frame members having lengths which differ from each other by equal multiples of a module M , so that their respective lengths may be equal to integral multiples of M plus a constant K , the structural members having portions between the adjacent ends of frame members, said portions having a cross-sectional dimension W in the direction of length of the frame members, the parts being so proportioned that when C equals the spacing of each of the frame members from said portions of the structural members at and between the ends of said frame members, $2C$ plus W plus K equals an integral multiple of M , the structural members also having respective lengths which differ by equal multiples of a module M , parallel frame members in the same plane having longitudinal central axes spaced from each other at multiples of the module M and certain of said members having repetitive fastening means disposed therealong, said means being spaced from each other lengthwise of the frame members at distances which have a uniform common divisor with the module M and being uniformly spaced from said longitudinal axes at equal distances, secondary frame elements extending between parallel frame members and secured thereto by connections with certain of the fastening means, the fastening means connected to opposite ends of individual secondary elements being spaced from one another at distances which differ by multiples of said module M .
12. A building of the type including members manufactured in quantity and preformed to avoid cutting in situ, comprising parallel vertical wall portions having their central planes spaced at multiples of a module M from each other, the wall portions being provided with uniform connecting means spaced at multiples of the module M longitudinally of the walls, and having a cross-sectional dimension w adjoining the connecting means, floor members extending between the wall portions and connected thereto by certain of said means, the lengths of the floor members differing from each other by multiples of M so that their lengths may equal an integral multiple of M plus a constant k , the wall portions and floor members being arranged so that $2c$ plus k plus w equals an integral multiple of M , when c equals the spacing of the end of a floor member from the adjoining part of a wall portion that has a cross-sectional dimension w .
13. A building having parallel frame portions defining walls and including parallel structural members, an elongate primary frame member spanning the distance between structural members in said parallel frame portions, an intermediate structural member parallel to the structural members in said frame portions, primary frame members at right angles to and spanning the distance between the intermediate structural member and structural members in said frame portions, uniform connections joining the frame members to the structural members, the frame members having lengths which differ from each other by equal multiples of a module M so that their respective lengths may be equal to integral multiples of M plus a constant K , the intermediate structural member having a portion at and between the adjacent ends of primary frame members, said portion having a cross-sectional dimension W in the direction of length of the frame members, the members being so proportioned that, when C equals the spacing of each of the frame members from the cross-sectional dimension of the structural member between the ends of the frame members, $2C$ plus W plus K equals an integral multiple of M , connecting means upon said primary frame members spaced uniformly at multiples of M , secondary frame members extending between parallel primary frame members and uniformly connected to said means, and wall plates or members substantially closing the spaces between said secondary members, each of said wall members having widths which differ

from the widths of like members only by integral multiples of said module M .

14. A building of the type having a frame constructed of parts that are manufactured in quantity and preformed to avoid cutting or fashioning in situ, comprising parallel frame portions defining outer walls and intermediate walls including parallel girts, floor members extending between the girts, uniform connecting means joining the ends of the floor members to the girts, the intermediate girts each having a cross-sectional dimension w between the floor members, the floor members having lengths differing from each other by multiples of a module M , so that their lengths may each be equal to integral multiples of the module M plus a constant k , the parts being so proportioned and arranged that $2c$ plus w plus k equals an integral multiple of M , when c equals the spacing of the ends of the floor members from the girts to which they are connected.

Signed by me at Boston, Massachusetts, this 10th day of December, 1929.

ALBERT F. BEMIS.
